UNITED STATES PATENT OFFICE.

CHARLES W. BLISS, OF WILMINGTON, DELAWARE, ASSIGNOR TO HIMSELF
AND H. A. BLAKE, OF SAME PLACE.

SMELTING-FURNACE.

SPECIFICATION forming part of Letters Patent No. 255,759, dated April 4, 1882.

Application filed March 30, 1881. (No model.)

To all whom it may concern:

Be it known that I, CHARLES W. BLISS, of Wilmington, Delaware, have invented certain new and useful Improvements in Smelting-Furnaces; and I do hereby declare the following to be a full, clear, and exact description of the same, reference being had to the annexed drawings, forming part hereof.

The nature of my invention will fully appear from the following specification and claims.

In the drawings, Figure 1 is a vertical sectional view of my furnace on line *z z* of Fig. 3, showing the steam-boiler in the interior, also the feeding-door; Fig. 2, a similar view on line *y y* of Fig. 3; Fig. 3, a horizontal sectional view on the line *x x* of Fig. 1; Fig. 4, a detached view of one of my fire-bricks, showing a grooved or recessed back.

20 A is the top or roof of the furnace; A', the sides or walls thereof.

B B are my fire-bricks, slightly converging below toward the foot of my fire-brick grate-cone C C. These fire-bricks B B have 25 spaces B' B' between them, and an annular space, B'', between their lower parts and the wall A'.

B''' B''' are projections to sustain the fire-bricks in place. The grate-bars C C have 30 spaces D D between them, and inclose a hollow conical space below.

E is a flue or recess in the back of bricks B, communicating below with the annular space B'' and openings K, and above with the 35 open space inclosed by the cover or top A.

G is a feed opening or door; H, a steam-boiler; H', a steam-conduit leading to an opening below to inject steam into the charge.

I is the foundation of the cone and fire-brick chamber, also forming a metal chamber.

F is an opening from the inner space of the cone to remove the charge; J, an opening to remove the slag.

K K are draft-holes.

45 The operation of my furnace is as follows: The fuel and charge are inserted through the door G, and are ignited below through door F. They lie upon and around the cone C. The charge is not piled in so as to lie above the holes K, as it would stop them up. The hollow cone grate will thus be seen to project well up through the mass of the charge.

Draft is supplied through draft-holes O, as many of which may be used as are found necessary. Draft is thus maintained from every 55 direction through slits B' to the mass, and most perfect combustion and thorough and almost simultaneous melting of the whole charge is secured. The annular space B'' may be used as a hot or cold air chamber, as jets 60 of either hot or cold air may be introduced thereto through the walls A' at one or more points. The steam-boiler H is heated by the heat of the furnace, or the steam may be carried from a boiler outside thereof, or the boiler may be set 65 in one side of the walls of the furnace to be heated therefrom. The openings L M are for the combined oil and steam jets—L for the steam and M for the oil. The steam and oil unite after passing through these openings, 70 and are then projected by the steam-pressure through one of the slits B', and then pass down through a slit, D, to the cone-chamber, beneath which oil burns with a fierce flame, and assists in the reduction of the mass. 75

The openings F and J are closed by means of clay during the reduction of the mass. Other shaped openings than those shown at D and B' might be used, but I prefer those shown; and the cone C might be altered in 80 shape, but I prefer this shape, as it is best calculated to sustain the weight of ore and carry the flame from beneath into the interior of the mass of ore. The molten metal passes from the chamber beneath the cone out through 85 the orifice F when the furnace is empty.

What I claim as new is—

1. In combination with the exterior walls of the furnace, an interior brick lining, B, set away from the outer wall, whereby an annular chamber, B'', is left between the lining B and said exterior wall, and openings B' extending from the bottom to near the top of the lining B, substantially as described.

2. In combination with the exterior walls 95 of the furnace, an interior brick lining provided with gradually-decreasing openings extending from the bottom to near the top, substantially as specified.

CHARLES W. BLISS.
